UNITED STATES PATENT OFFICE.

ANGUS MCNEIL, OF GLOUCESTER, MASSACHUSETTS.

COLLAPSIBLE BOAT.

1,303,700.

Specification of Letters Patent.

Patented May 13, 1919.

Application filed June 8, 1918. Serial No. 238,993.

To all whom it may concern:

Be it known that I, ANGUS MCNEIL, a citizen of the United States of America, and resident of Gloucester, in the county of Essex and State of Massachusetts, have invented new and useful Improvements in Collapsible Boats, of which the following is a specification.

This invention relates to collapsible boats and more particularly to life boats intended to be collapsed into compact form when not in use.

The principal objects of the invention are to provide a collapsible boat which is rigid and substantial when extended for use, which can be collapsed into a relatively small space when not in use, which can be extended or collapsed quickly and easily, and which is comparatively light in weight.

The cardinal features of the invention are as follows: The sides of the boat are constructed of flexible waterproof material and are held in extended position by arcuate ribs and gunwales extending longitudinally of the boat and being pivotally supported at their opposite ends so that they may be swung together to collapse the sides. The sides are held in extended position by spreaders pivotally supported on upright posts mounted on the keel, the spreaders being arranged to swing into the vertical central longitudinal plane of the boat to collapse the boat and being shaped to the vertical transverse contour of the boat so as to engage the longitudinal ribs and hold the sides in extended position when swung outwardly. The spreaders are arranged to engage the gunwales and hold them in extended position vertically as well as laterally. Trans-

verse seats are hinged at their opposite ends to a pair of the longitudinal ribs and at their centers are jointed so that they will fold into the vertical central longitudinal plane of the boat when collapsed. The seats also serve to hold the sides of the boat in extended position and are preferably supported at their centers by the vertical posts to which the spreaders are hinged. Floor sections may be hinged to the keel so as to fold upwardly into the vertical central longitudinal plane of the boat when the boat is collapsed.

The preferred embodiment of my inven-

tion is illustrated in the accompanying drawings, in which,—

Figure 1 is an elevation of the forward and central portions of the boat, the rear portion being omitted inasmuch as it is similar to the forward portion;

Fig. 2 is a central longitudinal section of the portions of the boat shown in Fig. 1;

Fig. 3 is a central transverse section of the boat looking forward;

Fig. 4 is a view similar to Fig. 3 showing the boat collapsed.

The embodiment of my invention illustrated in the drawings comprises, in general, a keel K which preferably consists of a rectangular wooden beam, a bow-stem B, a stern-post (not shown), which is similar to the bow-stem, both the bow-stem and stern post also preferably consisting of wooden beams, collapsible sides C of canvas or other material rendered impervious to water, gunwales G and ribs R pivotally mounted at their opposite ends on the bow-stem and stern-post respectively as will be described hereinafter, seats T, spreaders S hinged to spreader posts P, and floor sections F.

The ribs R are bow-shaped and are pivot- 80 ed or mounted in bearing members 1 secured to the bow-stem and stern-post respectively. These bearing members may be secured to the bow-stem and stern-post in any suitable manner and in the drawings I have shown 85 wood lugs 2 for fastening the members.

The upper bearing member to which the upper ribs are connected is bent over the top of the bow-stem as illustrated in Fig. 2 and the over-hanging flange 3 is secured to the 90 bow-stem by means of lugs 4. The other bearing members 1 extend laterally from the bow-stem and are provided with openings in their lateral extensions to receive the ends of the ribs, the ends of the ribs being bent into 95 alignment with the openings 5. The upper bearing member is provided with openings 6 to receive the ends of the upper ribs. The gunwales G are mounted along the inside of the upper ribs and are preferably formed of 100 rectangular wooden pieces, the ribs preferably being metal rods or tubes. The canvas sides C are secured to the keel by means of metallic plates 7 which are secured to the keel by means of rivets 8 and the sides are 105 folded inwardly over the upper ribs between

the ribs and the gunwales. The gunwales and upper ribs are preferably secured together by bands 9 of cord. The canvas sides are also secured to the ribs at intervals by means of bands 11 of cord or other suitable clips in order to maintain the ribs in properly spaced relationship when the sides are extended.

My improved means for maintaining the sides in extended position comprises spreaders S hinged to posts P. The posts P are secured to the upper side of the keel K at suitable intervals and may be braced by rods 12. The spreaders S are formed of rods or tubes into the shape shown which comprises vertical portions 13, curved portions 14 of substantially the same contour as the side of the boat when extended, and horizontal portions 15, the portions 15 having extensions 16 bent upwardly and extending through loops 17 at the ends of the portions 14 and thence somewhat beyond the loops 17. The vertical portions 13 are pivotally secured to the opposite sides of the post P by means of bands 18 and 19 surrounding the post P and the vertical portions 13, these bands being secured to the posts by means of rivets 20 passing through the central portions of the bands and posts. The loops 17 at the outer end of the spreader are bent inwardly at substantially 90 degrees so as to provide shoulders adapted to support the gunwales when the boat is extended. The portions 16 of the spreaders preferably extend slightly above the gunwales so that rings 21 secured to the gunwales by staples 22 may be placed over the projecting ends of the portions 16 of the spreaders to hold the parts together.

The seats T are pivotally connected to the second pair of ribs at their outer ends by means of hinges 23 and are jointed in the middle by means of hinges 24 so that the two halves of each seat may swing downwardly when the boat is collapsed. The seats are notched or recessed at the outer ends as indicated at 25 in Figs. 1 and 3 to receive the upper ends of the spreaders. In this way the seats can be disposed in the vertical transverse plane of the spreaders and may be supported on the spreader posts P.

While any desired number of spreaders and seats may be provided the boat illustrated in the drawings has three seats and two pairs of spreaders, a pair of spreaders being associated with each of the end seats but not with the middle seat. Each pair of spreaders is disposed on the side of the corresponding seat facing toward the center of the boat and when the boat is collapsed both pairs of spreaders swing toward the center of the boat. In order to support the middle seat at its center in the absence of spreader posts P I provide a supporting post P' especially for this purpose.

The floor sections F are pivotally connect-

ed to the upper side of the keel by means of double hinges 26 so as to swing upwardly into the vertical central longitudinal plane of the boat. The floor sections may rest at their outer ends upon pairs of ribs as shown in Fig. 3 or they may be supported at their outer ends directly upon the sides of the boat or in other suitable manner.

To collapse the boat the operation is as follows: The rings 21 are removed from the projecting ends of the spreaders, the floor sections are folded upwardly into the position shown in Fig. 4, the spreaders are then swung inwardly about their vertical axes into the position shown in Fig. 4 and the sides of the boat may then be collapsed into the position shown in Fig. 4, the seats T automatically folding into the position shown in Fig. 4. To extend the boat the operation is substantially reversed; the sides are swung outwardly into the position shown in Figs. 1 to 3, the spreaders are swung outwardly into extended position and at the same time the shoulders formed by loops 17 are forced under the gunwales, thus more positively supporting the gunwales and holding them in proper elevated position. The rings 21 are then placed over the projecting ends of the spreaders and the floor sections swung downwardly, when the boat is ready for use.

I claim:

1. A collapsible boat comprising flexible sides, a bow-stem, a stern-post and arcuate rods for holding the sides in extended position, the bow-stem and stern-post having fore-and-aft openings and the ends of the rods being bent to extend into the openings.

2. A collapsible boat comprising flexible sides, a bow-stem and stern-post, collapsible ribs extending between the bow-stem and stern-post for supporting the sides, and spreaders for holding the ribs in extended position, each of the spreaders comprising a rod bent into a loop having upper and lower horizontal portions and an outer portion bent to conform to the transverse contour of the boat.

3. A collapsible boat comprising flexible sides, a keel, a bow-stem and a stern-post at opposite ends of the keel, collapsible ribs extending between the bow-stem and stern-post for supporting the sides, a vertical post mounted on the keel in the central longitudinal region of the boat, and spreaders pivotally mounted on said posts to swing about vertical axes into said region to collapse the boat and into the vertical transverse plane of said post to hold the ribs in extended position.

4. A collapsible boat comprising a keel, a bow-stem, a stern-post, gunwales pivotally connected to the bow-stem and stern-post to swing downwardly alongside the keel, and spreaders pivotally mounted to swing about vertical axes disposed in the central longi-

tudinal region of the boat, the spreaders being arranged to support the gunwales.

5. A collapsible boat comprising a keel, a bow-stem, a stern-post, gunwales pivotally connected to the bow-stem and stern-post to swing downwardly alongside the keel, and spreaders pivotally mounted to swing about vertical axes disposed in the central longitudinal region of the boat, the spreaders 10 having shoulders to support the gunwales when the boat is extended.

6. A collapsible boat comprising a keel, a bow-stem, a stern-post, longitudinal ribs and gunwales pivotally connected to the bow-15 stem and stern-post to swing downwardly alongside the keel, and spreaders pivotally mounted to swing about vertical axes disposed in the central longitudinal region of the boat, the spreaders being arranged to 20 exert an outward force on the ribs and an upward force on the gunwales.

7. A collapsible boat comprising a keel, a bow-stem, a stern-post, longitudinal ribs pivotally mounted on the bow-stem and stern-25 post to swing downwardly alongside the keel, a vertical post mounted on the keel, spreaders pivotally mounted on the vertical post to hold the ribs in extended position, and a seat connected at its outer ends to a 30 pair of said ribs and jointed in the middle so as to fold downwardly when the ribs are swung down, the seat being disposed over said post so as to rest on the post when the boat is extended.

35 8. A collapsible boat comprising a keel, a bow-stem, a stern-post, longitudinal ribs and gunwales pivotally mounted on the bow-stem and stern-post to swing downwardly alongside the keel, a vertical post mounted 40 on the keel in the central longitudinal region of the boat, spreaders pivotally mounted on the said vertical post to swing about vertical axes into said region to collapse the boat and into the vertical transverse plane of the vertical post to hold the ribs in extended position, the spreaders having upright portions 45 at their outer ends to support the gunwales,

and a seat connected at its outer ends to a pair of said ribs and jointed in the middle so as to fold downwardly when the ribs are 50 swung down, the seat being disposed over said post so as to rest on the post when the boat is extended and the seat having recesses into which said upright portions of the spreaders extend when the boat is extended. 55

9. A collapsible boat comprising a keel, a bow-stem, a stern-post, longitudinal ribs pivotally mounted on the bow-stem and stern-post to swing downwardly alongside the keel, 60 a vertical post mounted on the keel, spreaders for holding the ribs extended, the spreaders being pivotally mounted on said vertical post to swing about vertical axes, a seat connected to a pair of said ribs at its outer 65 ends and jointed in the middle so as to fold downwardly, the seat being arranged to rest on said vertical post when extended, and floor sections pivoted to the keel so as to swing upwardly into the vertical central 70 longitudinal region of the boat, the parts being arranged so that the spreaders may be swung along opposite sides of the floor sections when the floor sections are swung upwardly and so that the seat folds over said 75 vertical post when the boat is collapsed.

10. A collapsible boat comprising a keel, a bow-stem, a stern-post, longitudinal ribs pivotally mounted on the bow-stem and stern-post to swing downwardly alongside 80 the keel, a vertical post mounted on the keel, spreaders for holding the ribs extended, the spreaders being pivotally mounted on said vertical post to swing about vertical axes, and floor sections pivoted to the keel so as 85 to swing upwardly into the vertical central longitudinal region of the boat, the parts being arranged so that the spreaders may be swung along opposite sides of the floor sections when the floor sections are swung up- 90 wardly.

Signed by me at Boston, Massachusetts, this 31st day of May, 1918.

ANGUS McNEIL.
